UNITED STATES PATENT OFFICE.

WILLIAM P. ADLETA AND OSEA M. ADLETA, OF DALLAS, TEXAS.

RAILWAY-CROSSING SIGNAL.

1,108,822.

Specification of Letters Patent. Patented Aug. 25, 1914.

Application filed June 14, 1913. Serial No. 773,801.

To all whom it may concern:

Be it known that we, WILLIAM P. ADLETA and OSEA M. ADLETA, citizens of the United States of America, residing at Dallas, in the county of Dallas and State of Texas, have invented new and useful Improvements in Railway-Crossing Signals, of which the following is a specification.

This invention relates to improvements in railway crossing signals and has particular application to an electrically energized signal of this class.

In carrying out the present invention, it is our purpose to provide a railway crossing signal whereby both a visual and audible signal will be given at the crossing in the event of a train approaching such crossing thereby advising pedestrians and others at the crossing or approaching the same of the proximity of the train.

It is also our purpose to provide a railway crossing signal which will embrace the desired features of simplicity, efficiency and durability; one which may be installed and maintained at a minimum expense and one which will be reliable and effective in operation.

With the above and other objects in view, the invention consists in the construction, combination and arrangement of parts hereinafter set forth in and falling within the scope of the claim.

In the accompanying drawing; Figure 1 is a plan view of a railway crossing showing the position of our improved signal with respect to such crossing. Fig. 2 is a vertical sectional view through the signal casing showing the inner mechanism in end elevation. Fig. 3 is a similar view taken at right angles to Fig. 2.

Referring now to the accompanying drawing in detail, the numeral 1 designates parallel lines of rails forming a railroad trackway over which trains or cars are adapted to travel, while the numeral 2 designates a roadway or a second trackway intersecting the lines of rails of the first trackway at right angles thereto.

Our improved crossing signal is indicated as an entirety by the letter S and is located adjacent to the point of intersection of the lines of rails 1, 1 and the roadway 2 so that a pedestrian or the operator of a vehicle upon the roadway 2 will be advised as to the proximity of a train on the lines of rails 1, 1. In the present instance, this crossing

signal comprises a hollow tubular post or standard 3 having one end embedded in the earth and the opposite end terminating a suitable or convenient distance above the ground.

Suitably secured to the upper extremity of the tubular post 3 is a casing 4 composed of some suitable material and of any desired outline. Arranged within this casing 4 and appropriately fastened to the bottom wall thereof is an electric motor 5 having keyed upon one extremity of the shaft of the armature thereof a pinion 6 meshing with a gear wheel 7 keyed upon a shaft 8 journaled in the end walls of the casing 4 and extending longitudinally of the latter above the motor 5. This shaft 8 has suitably fastened upon each end thereof a hub from which radiates a number of blades 9 adapted to rotate under the action of the shaft 8 and motor 5 so as to signal a person approaching the crossing from either side of the lines of rails 1, 1.

Suitably fastened to the top wall of the casing 4 is a bell or gong 10 disposed within the influence of a tapper 11 pivoted upon a bracket 12 arranged within the casing 4 and depending from the top wall thereof, the tapper projecting through the top wall of the casing and has the lower extremity of the shank or stem thereof equipped with a dog 13 disposed within the influence of a ratchet wheel 14 keyed upon the shaft 8 adjacent to the gear wheel 7. Thus, it will be seen that as the armature shaft of the motor 5 rotates motion will be transmitted to the shaft 8 through the medium of the pinion 6 and gear 7 thereby rotating the signal blades 9, while at the same time, the ratchet wheel 14 will rotate and so oscillate the hammer or tapper 11 to sound the bell or gong 10 whereby an audible as well as a visual signal will be given.

In order that the crossing signal will be effective at night, we mount upon the top of the casing 4 an electric lamp 15 connected in multiple in an electric circuit composed of conductors 16 and including the motor 5, a suitable source of energy such, for instance, as a battery 17, and a portion of the lines of rails 1, 1 at both sides of the crossing. In the present instance, the battery 17 is arranged within a housing 18 carried by the post 3 so that access may be had to the battery for replenishing or repairing the same.

It will be seen that the circuit of the motor and lamp is normally open and closed by the axles and wheels of a train entering the insulated portions of the lines of rails 5 1, 1.

It will, of course, be understood that the portion of the track included in the motor circuit 2 is of such length as to insure the giving of a signal at the crossing for a considerable length of time previous to the 10 train passing over the crossing.

We claim:

A railway crossing signal comprising a casing, a motor within said casing, a shaft journalized in the end walls of said casing and extending longitudinally thereof, driving connections between said motor and shaft, an electric lamp mounted upon the top of said casing, blades radiating from

the opposite ends of said shaft and movable across the path of the light rays from said lamp, a bell mounted upon said casing, a tapper for said bell, a ratchet wheel fixed to said shaft and adapted to actuate said tapper to sound the bell, an electric circuit including said motor and lamp, and means for closing said circuit whereby the motor and lamp will be energized and the shaft rotated to revolve the blades across the path of the light rays issuing from the 20 lamp and sound the bell. 25

In testimony whereof we affix our signatures in presence of two witnesses.

WILLIAM P. ADLETA.
OSEA M. ADLETA.
